DESIGN.

J. T. BENTLEY,

FLAG,

APPLICATION FILED MAY 21, 1918.

52,463.

Patented Sept. 24, 1918.

Inventor:

John T. Bentley,

By his Atty,

J. H. Richards.

UNITED STATES PATENT OFFICE.

JOHN T. BENTLEY, OF TENAFLY, NEW JERSEY.

DESIGN FOR A FLAG.

52,463.

Specification for Design.

Patented Sept. 24, 1918.

Application filed May 21, 1918. Serial No. 235,902. Term of patent 7 years.

To all whom it may concern:

Be it known that I, JOHN T. BENTLEY, a subject of the King of Great Britain, residing at Tenafly, in the county of Bergen and State of New Jersey, have invented a new, original, and ornamental Design for Flags, of which the following is a specification, reference being had to the accompanying drawing, forming a part thereof.

The design shown herewith is a composite design formed of the American, British, and French flags.

I claim:

The ornamental design for a flag, as shown.
JOHN T. BENTLEY.

Witnesses:

H. L. COFFIN,
P. A. FLEMM.
